ROTARY BLENDER ATTACHMENT

Earl Rutan, Pound Ridge, N. Y., assignor to Loral Electronics Corp., Bronx, N. Y., a corporation of New York

Application September 17, 1956, Serial No. 42,963

Term of patent 14 years

(Cl. D89—1)

Fig. 1

Fig. 2

Fig. 4

Figure 1 is a view in perspective of a rotary blender attachment showing my new design;

Figure 2 is a perspective view of the lid or closure portion thereof;

Figure 3 is a horizontal sectional view as seen from the plane 3—3 on Figure 1;

Figure 4 is a side elevational view of the lid or closure portion, partly in section.

I claim:

The ornamental design for a rotary blender attachment, as shown.
